United States Patent Office.

WILLIAM A. MUNN, OF MILWAUKEE, WISCONSIN.

Letters Patent No. 77,643, dated May 5, 1868.

IMPROVEMENT IN BLANKS FOR BODIES OF SHEET-METAL TEA AND COFFEE-POTS.

The Schedule referred to in these Letters Patent and making part of the same.

TO ALL WHOM IT MAY CONCERN:

Be it known that I, WILLIAM A. MUNN, of Milwaukee, in the county of Milwaukee, and State of Wisconsin, have invented certain new and useful Improvements in the Manufacture of Tin-Ware; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to tin-ware, and consists in manufacturing fancy and ornamental tin-blanks ready for use in forming the bodies of tea-pots, coffee-pots, and similar articles.

In the drawing—

Figure 1 represents a plan view of one of my blanks.

It is well known that of late years many useful and valuable improvements have been made in mechanical devices for manufacturing tin-ware. Many of these improved devices are expensive, and beyond the means of small manufacturers, and especially of those doing business in country places, at a distance from large manufacturing centres. As a consequence of this state of things, an extensive trade has sprung up in articles partially manufactured. The different parts going to form an article when complete, are purchased at the manufactory, sent or carried to any place desired, and there put together in the ordinary way.

For years past, the covers, breasts, and bottoms of kettles, boilers, and similar articles, made from tin or copper, have been made at the large factories by the use of expensive cutting and pressing-mechanism, and sold to the small dealers and manufacturers as new articles in the trade. These articles are thus furnished at a much cheaper rate than they cost when made in the ordinary way.

At the present time only the covers and trimmings of tea and coffee-pots are furnished and sold in this way as new articles in the trade. The bodies of the pots are cut out of the sheet tin after patterns, with which each shop has to be provided, and the work has to be made up plain and without ornament.

The object of my invention is to provide blanks stamped or pressed with fancy and ornamental designs, and cut into suitable shapes for being formed up at once into the bodies of tea or coffee-pots, as a new article in the trade. By the use of these, small dealers and manufacturers in the city and in the country can readily and cheaply make up fancy and ornamental pots.

In manufacturing these blanks, I cut out the blanks A from sheet tin, of the requisite size and shape to make up into tea and coffee-pots of the usual form. These blanks I then stamp or press, in any ordinary way, either with a screw-press or drop-stamp, with a fancy ornamental raised border, B, and with raised fancy and ornamental designs, C, surrounded with a raised border, D, as shown in the drawing.

It is obvious that these designs may be changed, so as to give a variety of patterns, to suit the taste of the manufacturer or his customers.

I press or stamp up these designs or figures in such a manner as not to injure or mar the tin, so that the pots made up with these blanks will both last quite as long, but will also be as susceptible of being highly polished as those made from plain sheet tin.

In this way I am able to furnish a "new article in the trade," and to meet a want long felt by tinmen doing business in a small way, either in our large cities or in the country. My "blanks" can be furnished at a very little advance on the price of sheet tin. They can be conveniently packed, so that the cost of transportation will be about the same as sheet tin. With them small dealers can make up fancy and ornamental work without the necessity of investing their capital in expensive tools; and those residing in distant parts of the country can have this kind of work made up where they live, and thus save the cost of transporting bulky articles, so bulky, in fact, that they cannot be profitably transported.

Having thus described my invention, what I claim is—

As a new article of manufacture, tin-blanks to form the bodies of tea and coffee-pots and similar articles, when stamped or pressed with fancy and ornamental designs, substantially as herein described.

W. A. MUNN.
